H. F. HECKER

PANEL FOR CEDAR CHESTS AND OTHER ARTICLES

Filed April 2, 1924

INVENTOR.
HERMAN F. HECKER.
BY HIS ATTORNEY.

James T. Williamson

UNITED STATES PATENT OFFICE.

HERMAN F. HECKER, OF OXBORO, MINNESOTA.

PANEL FOR CEDAR CHESTS AND OTHER ARTICLES.

Application filed April 2, 1924. Serial No. 703,698.

To all whom it may concern:

Be it known that I, HERMAN F. HECKER, a citizen of the United States, residing at Oxboro, in the county of Hennepin and State 5 of Minnesota, have invented certain new and useful Improvements in Panels for Cedar Chests and Other Articles; and I do hereby declare the following to be a full, clear, and exact description of the invention, 10 such as will enable others skilled in the art to which it appertains to make and use the same.

This invention relates to a panel construction, and while the same is particularly 15 adapted for use as the panel for the top and side walls of a chest, such as a cedar chest, yet the same is capable of many other applications, such as the panel for the top of a table for wainscoating, screen construction, 20 etc.

It is an object of this invention to provide a simple and strong construction of a panel using small pieces or strips of wood such as can be obtained from the waste cuttings of 25 lumber, which panel may be constructed to afford different patterns of great beauty.

It is a further object of the invention to provide a panel formed of pieces of material, as above described, which pieces are arranged in a novel manner and held in assembled relation by a novel combination of 30 means.

It is a further object of the invention to provide a cedar or other chest using said 35 panel and having novel features of construction.

These and other objects and advantages of the invention will be fully set forth in the 40 following description made in connection with the accompanying drawings in which like reference characters refer to the same parts throughout the different views, and in which,

Fig. 1 is a top plan view of a cedar chest 45 using the panel of the present invention;

Fig. 2 is a view in front elevation of said chest;

Fig. 3 is a vertical section taken on the line 3—3 of Fig. 2, as indicated by the arrows, shown on an enlarged scale;

Fig. 4 is a partial plan view of the panel showing the securing means;

Fig. 5 is a vertical section taken on the line 5—5 of Fig. 4, as indicated by the arrows;

Fig. 6 is a top plan view of a locking member used;

Fig. 7 is a view in front elevation of the locking means shown in Fig. 5;

Fig. 8 is a plan view showing a slightly 60 modified form; and

Fig. 9 is a vertical section taken on the line 9—9 of Fig. 8, as indicated by the arrows, Figs. 4 to 9 also being shown on an 65 enlarged scale.

Referring to the drawings, particularly to Figs. 1 and 2, a plurality of somewhat elongated members 1 are shown, which members are of rectangular cross section, and in the embodiment of the invention illustrated, are 70 shown as substantially square in cross section. The members 1 are illustrated as contacting at each side the center member 1^a, the member 1^a, however, preferably being formed of a different kind of wood having a 75

darker color. In one practical embodiment of the invention, the members, shown as of lighter color are made of basswood while the darker pieces 1^a are of cedar. It will be seen from Fig. 1 that a plurality of the 80 pieces 1 and 1^a are assembled together in a group extending longitudinally of the panel, the members contacting at one side and having their outer surface flush at both sides of the panel. Between the ends of each 85

group of the members 1 and 1^a are disposed shorter members 2 and 2^a, the members 2^a being of darker wood than the members 2 and both the members 2 and 2^a having their longitudinal center lines disposed at an angle 90 to the longitudinal center lines of the members 1 and 1^a, this angle, in the embodiment of the invention illustrated, being shown as a right angle. It will be noted that the length of the members 2 and 2^a is 95 the same as the combined width of the members 1 and 1^a forming one of the groups of the latter. The groups of the members 2 and 2^a therefore are disposed between the ends of the groups of the members 1 and 1^a, 100 the different groups thus being arranged in alternate relation longitudinally of the panel. This alternate arrangement of the groups of members is continued throughout the panel, the said groups being arranged 105

in rows and, as shown in Figs. 1 and 2, the groups formed of the members 2 and 2^a preferably are arranged in staggered relation throughout the panel and also preferably centrally of the groups formed of the 110

members 1 and 1^a. A panel is thus formed having a thickness equal to the thickness of the different members and the members 1, 1^a, 2, 2^a, preferably will be glued together along their contacting sides and ends. In order to hold the members tightly together in close fitting arrangement, the groups of the members 1 and 1^a are pierced and joined together by elongated members 3 shown as headed and nutted bolts with the heads and nuts thereof countersunk in the outer members 1 and 1^a. As shown in Figs. 1 and 2, one of the members 3 preferably is used between each of the groups formed of the members 2 and 2^a. Said members 3, therefore, firmly clamp and hold the members 1 and 1^a in close fitting and compact relation. In order to securely hold the members 2 and 2^a, dowel pins 4 and 5 are secured therein, which pins project into the ends of the adjacent members 1 and 1^a, as shown in Figs. 4 and 5. The dowel pins 4 are longer than the dowel pins 5 and project through the members 2^a, as shown, into the members 2, while the dowel pins 5 project only into the adjacent members 2^a. By means of the dowel pins 4 and 5, therefore, the members 2 and 2^a are prevented from any movement transversely of the plane of the panel.

In the structure of the chest illustrated, edge strips 6 and 7 are used surrounding the panel forming the top of the chest, the members 6 extending at the side and the members 7 at the ends of said panel. The shape of the members 6 and 7 in cross section, respectively, is shown in Fig. 3 where it is seen that the member 6 extends under and is set or rabbeted into the undersurface of some of the members 1 and it will, likewise, be set or rabbeted into the adjacent members 2 and 2^a. The strips 6 and 7, preferably are held in shape by screws 8 extending into the adjacent members 1. Outer strips 9 and 10 extend around the strips 6 and 7, respectively, and the strips 6 and 9 are mitered at the corners with the strips 7 and 10. In order to hold the said strips firmly in position, a key member 11, illustrated in Figs. 6 and 7, is used. Said key member has wings 11^a adapted to extend in horizontal slots 6^a formed centrally of the members 6, 9, 7 and 10, as shown in Fig. 2. The member 11 also has upper and lower projecting ribs 11^b extending centrally thereof adapted to be disposed in slots 7^a formed at the meeting edges of the strips 6 and 9 and 7 and 10, respectively, the top and bottom surfaces of the ribs 11^b lying flush with the top and bottom surfaces of said strips. In order to form a flanged lid, a strip 12 is secured to the bottom side of the strips 6 and 9 and a similar piece will be secured to the bottom of the strips 7 and 10. Said piece 12 has another strip 13 depending therefrom and of less width than

the members 12. Said members 12 and 13 will be secured to the strip 9 by suitable dowels 14 or suitable screws and it will be understood that a strip similar to the strip 13 will extend to the ends of the chest. The side and end panels of the chest will be formed in a manner similar to the panel described for the top and will be formed of similar members 1 and 1^a and 2 and 2^a, which will be bound together by similar bolts 3 and dowel pins 4 and 5. The side and end panels are surmounted by strips 15 to the top and at the inner edge of which are secured narrower strips 16 forming a flange on the box alongside of which the flange strip 13 on the lid is adapted to fit or be disposed, it being understood that there will be similar strips 16 at the ends of the chest. Thin corner strips 17 are also shown extending vertically at the ends of the side and end panels and between the strips 15 and similar strips 18 at the bottom of the chest. The lower strips 18 are connected to bottom strips 19 extending around the four sides of the chest. If desired, a quarter round strip 20 may be disposed at the inside of the lid in the angle formed by the strip 6. The rear side of the chest will be similar to the front side and hinges 22 will connect the strip 13 at the rear with the strip 15 whereby the chest is provided with a hinged lid.

From the above description it will be seen that applicant has provided a strong and efficient panel adapted for use in a rectangular chest, as illustrated, and it will also be seen that such a panel may be used in many other applications. The entire panel is made of small pieces and by the connecting means described, the said panel has great strength and rigidity and the pieces thereof are held in properly assembled and close fitting relation. It will be seen that the number and arrangement of the strips 1, 1^a, 2 and 2^a can be varied with the corresponding change in the pattern. With the different colored wood used, the effect of the panel is very beautiful and a simulation of a basket weave is produced. By utilizing small pieces the panel can be very inexpensively made and yet the same is as strong or stronger than a panel made of much larger pieces.

In Figs. 8 and 9, a modification is shown in which the members 1 and 1^a are made of greater length and some or all of the groups of the transverse members 21 and 21^a are of considerably less thickness than the members 1 and 1^a and are fitted thereinto with a dovetailed joint. Such construction can be used where cheap pieces suitable for the members 1 and 1^a are available of considerable length and it will be seen that thinner stock could be used for the members 21 and 21^a which correspond to the members

2 and 2^a. It will be noted, however, that in the form shown in Figs. 1 to 4, the pattern extends entirely through the panel so that the panel is the same on both sides. This, of course, would not be true of the structure shown in Figs. 8 and 9.

The invention has been amply demonstrated in actual practice and found to be very successful and efficient. The panel 10 formed is of great beauty and at the same time, forms a very rugged and durable construction. It is well known that with such assembled structures that in time some of the pieces tend to separate so that unsightly 15 cracks are produced. This tendency and result are prevented in applicant's construction by the tension members 3 extending transversely of the pieces to hold the same in close fitting condition in which 20 they were originally assembled.

It will, of course, be understood, that various changes may be made in the form, details, arrangement and proportions of the parts without departing from the scope of 25 applicant's invention, which, generally stated, consists in a device capable of carrying out the objects above set forth and in the novel structures and combinations defined in the appended claims.

30 What is claimed is:

1. A panel formed of adjacent rows of spaced groups of pieces, said panel comprising two sets of groups, said pieces being of rectangular cross section, each group of 35 one set comprising a plurality of similar pieces arranged longitudinally of said panel and the other set of groups each comprising a plurality of similar pieces having a length equal to the width of the groups of 40 said first mentioned set and disposed at an angle to the pieces of the groups of said first mentioned set, all of said pieces having their exposed surfaces at one side of the panel in one plane, and clamping means extending transversely of said panel through 45 the groups of said first mentioned set and between the groups of said second mentioned set.

2. A panel having a plurality of groups 50 of longitudinally extending pieces of rectangular cross section and a plurality of groups of shorter pieces of rectangular cross section disposed between the ends of said first mentioned groups and having the pieces 55 thereof disposed at an angle to the pieces in said first mentioned groups, spaced securing means extending transversely of said first mentioned groups and through the pieces thereof intermediate their ends, and fastening means extending from the ends of 60 and longitudinally of the pieces of said first mentioned groups into the pieces of the second mentioned groups.

3. A panel for a cedar chest or other article comprising alternately arranged groups

of pieces of substantially rectangular shape in cross section, the pieces in one set of said groups extending longitudinally of said panel and the pieces in the other set of groups extending transversely of said panel, 70 the length of the last mentioned pieces being equal to the combined width of the pieces in the groups of the first mentioned set, all of said pieces having their exposed surfaces in one plane, and clamping means 75 extending through the pieces in the first mentioned set of groups intermediate the ends thereof and between the groups of said other set.

4. A panel for a cedar chest or other article comprising a series of groups of longitudinally extending pieces of rectangular cross section, said groups being spaced at their ends, and other groups of transversely extending members interposed between said 80 ends and comprising pieces extending at right angles to the pieces of said first mentioned groups, clamping bolts extending transversely through the first mentioned groups and pieces thereof between the second mentioned groups, and dowel pins extending from the ends of the pieces of said first mentioned groups into the pieces of 85 said second mentioned groups and transversely thereof.

5. A panel formed of adjacent longitudinal rows, each comprising a series of groups of longitudinally extending contacting pieces of rectangular cross section, said groups being spaced at their ends, and groups of transversely extending members of rectangular cross section interposed between said ends, said members extending at right angles to said pieces, said groups in the adjacent rows being arranged in staggered relation, said members and pieces having their exposed surfaces in one plane, clamping means extending transversely through the pieces in said first mentioned groups and between said second mentioned 105 groups, and holding means extending from the ends of said pieces into and transversely of said members.

6. A rectangular panel having strips extending about its edges having their adjacent ends mitered at the corners of said panels, said mitered ends of said strips being provided with central slots extending parallel to the sides of said panel and the end of said strips being cut away to form 110 slots therebetween extending through said panel, and a key member having side portions disposed in said first mentioned slot and having top and bottom ribs disposed in said last mentioned slot.

7. The structure set forth in claim 6, the vertical sides of said first mentioned slots converging inwardly of said panel and said key member having its outer edges flush with the edges of said panel.

8. A rectangular panel comprising continuous longitudinal side pieces and continuous transverse end pieces mitered and keyed together at the corners of said panel
5 and also comprising two sets of groups of pieces rectangular in cross section, the groups being respectively alternately arranged in rows between said side and end pieces, one set of groups each comprising
10 a number of pieces extending longitudinally of the panel and the other set of groups each comprising a similar number of shorter pieces extending transversely of the panel, the length of said shorter pieces being equal
15 to the combined width of the longer pieces in a group of the first mentioned set, clamping members extending through said first set of groups and pieces thereof transversely of said pieces and between the ends of

said pieces and also between the groups of 20 the second mentioned set, and means projecting from the ends of said longer pieces into the sides of the adjacent shorter pieces.

9. A panel made up of a plurality of pieces of one length and a plurality of pieces 25 of shorter length, said pieces being respectively arranged in groups, said groups being arranged in rows extending longitudinally of said panel, the groups of longer pieces having the pieces therein extending 30 longitudinally of said panel and the groups of shorter pieces being disposed between said last mentioned groups, said shorter pieces extending at an angle to said longer pieces and having a length equal to the combined width of a group of the longer pieces. 35

In testimony whereof I affix my signature.

H. F. HECKER.
